UNITED STATES PATENT OFFICE.

FRED MONTGOMERY HENSHAW, OF LAKE CHARLES, LOUISIANA, ASSIGNOR OF ONE-HALF TO GEORGE WILLIAM CLINE, OF LAKE CHARLES, LOUISIANA, AND ONE-HALF TO ERLE N. R. HENSHAW, OF HOUSTON TEXAS.

SPRING-CUSHION.

1,325,092.

Specification of Letters Patent. Patented Dec. 16, 1919.

Application filed March 1, 1919. Serial No. 280,090.

To all whom it may concern:

Be it known that I, FRED M. HENSHAW, a citizen of the United States, residing at Lake Charles, in the parish of Calcasieu and State of Louisiana, have invented certain new and useful Improvements in Spring-Cushions, of which the following is a specification, reference being had to the accompanying drawings.

10 This invention relates to spring cushioning devices, and particularly to cushioning devices wherein the cushioning effect is secured by the expansion of a coiled contractile spring.

15 The general object of my invention is to provide a spring cushioning device which may be used for a large number of different cushioning purposes, in machines, furniture, and in many other different situations.

20 And a further object is to provide a device of this character for the purpose of obtaining a cushioning effect between two parts or objects by the use of a coiled contractile spring arranged in the form of an annulus 25 and which is radially expanded by the movement of said parts relatively toward each other and contracted upon the release of pressure on said parts.

25 My invention is illustrated in the accompanying drawings, wherein:—

Figure 1 is a vertical sectional view of a cushioning device constructed in accordance with my invention;

30 Fig. 2 is a like view to Fig. 1, but showing the cushioning device compressed;

Fig. 3 is a top plan view of the construction shown in Fig. 1, but with the disk 16 partly broken away;

35 Fig. 4 is a vertical sectional view of a modified form of the cushion shown in Fig. 1.

In these drawings, 15 and 16 designate two parts or members which are to be normally held apart, but which are adapted under 40 pressure or strain to be moved toward each other. The member 16 is flat and disk-shaped in the embodiment illustrated, while the member 15 is tapered or semi-conical, the small end of the member 15 being disposed 45 toward the member 16. Extending from the member 16 is a centrally disposed post 17, as it may be termed, which extends through an opening in the center of the member 15 and is provided with a head 18 larger in

diameter than said central opening and 55 which, when the parts are expanded, bears against the side wall of the member 15 an appreciable distance from the opening of the member 15.

Surrounding the connecting member 17 or 60 post and urging the members 15 and 16 apart, is a coiled spring 19 which is first coiled to form the usual helix and is then bent in a circle so that the spring forms a 65 resilient annulus formed by a plurality of coils. The confronting opposite ends of the spring are brought together and faced and then wrapped with wire, as at 20, or these confronting ends of the spring may be connected to each other in any other desired 70 manner. It will be seen that with this construction the coils of the spring are disposed radially relative to the central post 17 and that the tapering or conical upper surface of the member 15 is engaged by these coils of 75 the spring. Now it will be obvious that when the members 15 and 16 are forced toward each other, the conical or tapering face of the member 15 will act to expand the spring by urging the coils thereof radially 80 and that as soon as pressure is released, the coils will contract and exert a wedging action upon the centrally inclined or tapering inner surface of the member 15, thus urging the member 15 outward on the post 17 until 85 the head 18 has a firm bearing upon the inner face of the member 15.

It will be obvious that the member 15 must be tapered, and it will be obvious that as illustrated in Fig. 4 both the members 15 90 and 16 may be tapered if the spring is of sufficient size, and that provision must be made for the movement of the post 17 or connecting member, but that otherwise than this the members 15, 16, and 17 may be 95 constructed in many different ways to secure a cushioning effect between many different parts.

This spring cushion may be used as a spring for the seats of chairs or seats of 100 automobiles, or as bed springs. This device can also be used as means for holding valves to their seats in place of the ordinary coiled compression springs. The springs may be used as shock absorbers and, indeed, the 105 principle of this cushion may be applied in a large number of different ways without departing in any way from the spirit of the

invention. My invention, therefore, may be embodied in many different forms and for many different purposes.

I claim:—

- 5 1. A cushioning device including two elements movable toward or from each other, one of said elements having a centrally tapered face confronting the other element, and a coiled contractile spring disposed between the two elements and formed into an annulus concentric to the axis of the two elements, said spring acting against the tapering face of said element so that a movement of said elements toward each other will cause the spring to be expanded against its tension.
- 10 2. A spring cushion including two coacting elements movable toward or from each other, one of said elements having a centrally tapered inner face, means limiting the outward movement of the elements relative to each other, and a radially elastic annulus disposed so as to surround the axis of said tapered member so that when said tapered member is moved toward the other member it will expand the annulus.
- 15 3. A spring cushion comprising two elements, one of said elements having a centrally tapered face confronting the other element, a centrally disposed headed member engaging the two elements and restricting their movement away from each other but permitting

movement toward each other, and a resilient annulus composed of a helically coiled spring surrounding said connecting member resiliently urging both of said elements away from each other, said tapered face extending into the central opening of the annulus and exerting an outward wedging action thereon in all directions when said elements are moved toward each other.

4. A cushioning spring comprising a disk-like element having a centrally disposed post, an element having a central opening through which the post loosely passes, said element being concavo-convex and having its convex side confronting the disk-shaped element and said convex side being substantially tapered centrally, the post having a head at one extremity disposed within the tapered element and limiting the movement of said elements away from each other, and an annulus disposed concentric to the post and formed of a helically coiled spring, the tapered face of said element being movable into the central opening of the annulus so as to expand the coiled spring when the elements are moved toward each other.

In testimony whereof I hereunto affix my signature in the presence of two witnesses.

FRED MONTGOMERY HENSHAW.
